UNITED STATES PATENT OFFICE.

WILLIAM DALE, OF NEW YORK, N. Y.

COMPOSITE TILE ROOFING.

SPECIFICATION forming part of Letters Patent No. 226,983, dated April 27, 1880.

Application filed December 3, 1879.

To all whom it may concern:

Be it known that I, WILLIAM DALE, of the city, county, and State of New York, have invented certain new and useful Improvements 5 in Composite Tile Roofing, of which the following is a specification.

This invention relates to an improvement in that class of composite roofing composed of tiles formed by filling a series of dish-shaped 10 cast-iron plates with a suitable composition concrete applied in a plastic state and setting said tiles in a suitable supporting frame. These plates may or may not be provided with illuminating-openings covered by glass panes 15 or lenses held in place by the concrete; but as this improvement relates only to forming a water-proof joint between the tiles it is equally applicable whether said tiles have illuminating-windows or not.

20 In the accompanying drawings I have represented my improvement as applied to a roof provided with illuminating-windows.

Figure 1 is a plan view of a portion of two adjacent sectional tiles with a portion of their 25 surrounding and supporting frame, the upper part of said figure showing the glass lenses and concrete inserted, while the lower part shows only the naked cast-iron plate. Fig. 2 represents a cross-section in line $x x$, Fig. 1.

30 A is the tile-plate; A', a portion of the supporting-frame; B, the illuminating-apertures; B', the glass panes or lenses, and C the concrete filling.

The tile-plates are cast with ribs a and a' , 35 crossing each other at right angles, so as to form a separate cell for each glass lens. These ribs rise only about half as high as the surrounding rim of the tile-plate, so that when the concrete is inserted they are completely 40 covered and concealed. The said rim at the two sides of the tile-plates which come together is considerably higher than at the ends, forming vertical flanges, as shown at D, Fig.

45 2. The tile-plates are so set in the supporting-frame as to leave a small space between the

flanges of their adjacent sides, as shown in Fig. 2, and are screwed down to a cross-bar of said frame, as shown at A², Fig. 2.

The concrete and glasses may be inserted either before or after setting the tiles in the 50 frame.

I form a water-proof joint between the adjacent tiles by filling the space between them with oakum or other suitable calking material, or iron borings and a solution of sal-ammoniac, so as to form a rust-joint, or by inserting oakum at the bottom and iron borings and sal-ammoniac at the top; or said tile-plates may be placed in close contact with each other, and nothing inserted between the flanges. In 55 either case I cover said joint with a hood, D, in the form of an inverted gutter, made of sheet-copper or other sheet metal with projecting flanges d on each side, which are screwed down upon lugs d' , cast upon the tile-plates. This cover, being made of flexible 60 sheet metal, will expand and contract to adjust itself to any expansion or contraction of the cast-iron tile-plates, and thus secure a perfectly water-proof joint whether any calking 65 material is inserted between the tiles or not.

What I claim as my invention is—

1. The pan-shaped cast-iron tiles filled with concrete, and having projecting flanges adapted to be capped by a sheet-metal hood, substantially as set forth. 75

2. In a roof composed of a series of pan-shaped cast-iron tiles filled with concrete, as described, with projecting flanges at their adjacent edges, the hood D, made of flexible sheet 80 metal, covering the joint between the tiles, substantially as set forth.

In testimony that I claim the foregoing I have hereunto set my hand in the presence of the subscribing witnesses.

WILLIAM DALE.
